UNITED STATES PATENT OFFICE.

HAROLD T. DAHLY, OF MINNEAPOLIS, MINNESOTA, ASSIGNOR TO SEVERINA DAHLY,
OF MINNEAPOLIS, MINNESOTA.

WASHBOARD.

1,134,517.

Specification of Letters Patent.

Patented Apr. 6, 1915.

Application filed December 17, 1914. Serial No. 877,774.

To all whom it may concern:

Be it known that I, HAROLD T. DAHLY, a citizen of Canada, residing at Minneapolis, in the county of Hennepin and State of Minnesota, have invented certain new and useful Improvements in Washboards, of which the following is a specification.

This invention relates to certain new and useful improvements in wash-boards and has as its primary object to provide an article of this character which will, while being so formed as to furnish a wash-board of novel construction, be constructed of relatively few individual elements which may 15 be readily assembled to thus produce a construction capable of ready and inexpensive manufacture.

The invention has as a further object to provide a wash-board having a rubbing surface or working element of improved construction which will be composed of a plurality of individual rubbing members and wherein the said members will be so mounted and connected as to form a rubbing surface 25 or working element of a single unit which may be bodily connected with the other elements of the device.

A further object of the invention is to provide a resilient support for the rubbing surface or working element at its lower extremity and to so form said working element that it will be maintained firmly seated against the said support.

The invention has as a still further object 35 in this connection to provide a construction wherein the said resilient support for the working element will normally resiliently engage said element for yieldably maintaining it seated in position.

Other and incidental objects will appear as the description proceeds and in the drawings wherein I have illustrated the preferred embodiment of my invention and wherein similar reference characters designate 45 corresponding parts throughout the several views, Figure 1 is a front elevation of my improved wash-board partly broken away, Fig. 2 is a vertical sectional view taken on the line 2—2 of Fig. 1 and more 50 particularly illustrating the construction of the rubbing surface of working element employed, Fig. 3 is a horizontal sectional view also particularly illustrating the construction and mounting of the working element, 55 Fig. 4 is a fragmentary sectional view par-

ticularly illustrating the manner in which the channel members of the working element are engaged by the resilient support for the said element, Fig. 5 is a fragmentary perspective view particularly illustrating the 60 construction of the channel members at their lower ends as well as the manner in which the said channel members are disposed to seat upon the resilient support therefor, and Fig. 6 is a fragmentary sectional view showing the connection between the strips engaging the resilient support of the working element and the cross-piece of the wash-board.

Referring more particularly to the drawings, it will be seen that my improved wash-board includes the side members or stiles 10 arranged in substantially parallel relation to each other and which are connected at their upper extremities by a cap 70 piece 11. The confronting faces of the stiles 10 are longitudinally grooved as at 12 and removably fitting in the said grooves and in a suitable groove formed in the cap piece 11 is a head board 13. Secured at its extremities in any suitable manner between the stiles 10 and having a suitable groove 14 formed 75 in the adjacent face thereof to receive the lower edge of the head board 13 is a cross-piece 15, the lower face of the said cross-piece being straight from end to end and unobstructed.

Removably fitting in the grooves 12 of the stiles is a rubbing surface or working element designated as a whole at 16 in Fig. 1 90 of the drawings. More particularly, the said working element includes the confronting channel members 17 slidably fitting within the grooves 12, a plurality of weft wires or member 18 having their extremities 95 engaged within the said channel members, and preferably, a pair of combined warp and truss members 19. The channel members 17 are each preferably formed from a single piece of suitable resilient sheet metal 100 bent upon itself to provide the side walls 20 and a connecting wall 21 which extends at substantially right angles to the side walls. The grooves 12 are of such contour as to snugly receive the channel members 17, 105 the connecting walls 21 of the said members bearing against the bottom walls of the said grooves while the side walls 20 of the said members are normally disposed to expand to resiliently engage against the side walls 110

of the said grooves. It will thus be seen that the channel members 17 will firmly seat within the grooves 12 when positioned therein.

- 5 The upper ends of the channel members 17 may be closed in any suitable manner, and at the lower ends thereof, the side walls 20 are extended beyond the connecting wall 21 to provide lugs 22 which are bent inwardly toward each other to assume an overlapping relation and thus close the adjacent ends of the members. Preferably, the lugs 22 are bowed longitudinally to extend inwardly between the side walls 20 of the
- 10 members 17 at the adjacent extremities thereof to thus form upon the outer faces thereof, concave seats 23, the purpose of which will presently appear.
- 15

Extending transversely between the channel members 17 are the weft wires or members 18, the said members being arranged in superposed relation to rest upon each other and having their extremities freely received within the channel member 17.

- 20
- 25 Intermediate their extremities, the weft wires are arranged to extend upon one side of one of the truss members 19 and then upon the opposite side of the other truss member, the said truss members being preferably spaced at points equidistant from the vertical center line of the working element 16 upon each side thereof and being arranged substantially parallel with the channel members 17. In this connection, it should be observed as best shown in Fig. 3 of the drawings, that adjacent weft wires 18 are threaded over the truss members 19, which as will be understood from the preceding description, thus constitute a warp members, in reverse relation so that adjacent weft wires will intersect each other at a point substantially midway between the said truss members and thus provide a relatively smooth working surface medially of the working element, while at points adjacent the truss members 19, the said weft wires will provide a relatively rough working surface.
- 30
- 35
- 40
- 45

The weft wires 18 are preferably formed from suitable resilient material of a gage adapted for the purpose while the truss members 19 may each be formed from a strip of suitable metal. Particular attention is now directed to the fact that since the extremities of the weft wires 18 are freely received within the channel members 17, the distance between the side walls of the said channel members being greater than the diameter of the weft wires, the crossing of the weft wires upon the truss members 19 in the alternate manner previously set forth, will normally cause adjacent extremities of said wires to resiliently engage against opposite side walls of the said channel members. This is also best shown

in Fig. 3 of the drawings, and it will be observed that by such arrangement, slight movement of the extremities of the said weft wires between the side walls of the channel members will be permitted under pressure exerted upon a garment passing over the working element adjacent the stiles 10 from either one side or the other of the said working element as the case may be.

It will now be seen that the working element 16 provides working surfaces upon each side thereof of three different characters, first, the relative smooth working surfaces formed medially of the working element at the intersection of the members 18 between the members 19, second, the relatively rough working surfaces provided immediately adjacent or over the truss members 19, and third, the relatively rough yieldable working surfaces provided by the extremities of the said members 18 adjacent the stiles 10. Consequently, as will be observed, I provide a working element possessed of obvious important advantages, in that each side of the working element presents working surfaces each adapted for a particular purpose. For instance in the washing of lace, the relatively smooth working surfaces may be used, for heavier fabrics, the relatively rough working surfaces could be used, while, were it found very difficult to remove dirt from a garment, the yieldable working surfaces referred to, could be employed.

From the preceding description, it will be observed that the working element 16 and comprising the channel members 17, the weft wires 18, and the truss members 19, constitutes as an entirety, a single unit which may be readily placed in position between the stiles 10, as shown in Fig. 1 of the drawings, by moving the channel members 17 longitudinally within the grooves 12, the said grooves opening at their lower extremities through the beveled faces 24 of the said stiles. As more particularly shown in Fig. 6 of the drawings, the uppermost of the weft wires 18 is arranged to seat against the adjacent lower face of the cross-piece 15 with the upper extremities of the channel members 17 abutting the said cross-piece. The cross-piece 15, therefore provides an abutment for the working element 16 at its upper extremity and the adjacent upper extremities of the truss members 19 are passed through the said cross-piece as shown in Fig. 6 to enter the groove 14 as more particularly shown in Fig. 2. The adjacent terminals of said truss members are then bent over to form suitable lugs 25 engaging within the said grooves. In this connection, and as will be best observed upon reference to Fig. 2 of the drawings, attention is called to the fact that the adjacent lower edge of the head board 13 is disposed to seat upon

the said lugs 25, and said board thus tends to maintain the truss members firmly connected with the cross-piece 15.

Extending transversely between the stiles 10 at the adjacent lower extremities of the channel members 17 and passing through the grooves 12 is a resilient supporting member 26. The supporting member 26 is preferably formed from a length of suitable resilient wire and at its extremities is passed through suitable openings formed in the stiles 10, having its terminals bent laterally as at 27 to engage against the outer edges of the said stiles. The purpose of the concave seats 23 formed in the lower extremities of the channel members now becomes apparent since the supporting member 26 will normally rest within the said seats to support the working element 16 therebetween and the cross-piece 15.

At their adjacent lower extremities, the truss members 19 are looped around the member 26, as shown at 28, and particular attention is now directed to the manner in which the member 26 is caused to resiliently engage against the lower extremities of the channel members 17 for yieldably holding the said members seated at their upper extremities against the cross-piece 15. In looping the members 19 around the supporting member 26, the said supporting member is bowed upwardly intermediate its ends, as best shown in Figs. 1 and 5 of the drawings, causing it to flex upwardly from points adjacent the bottom walls of the grooves 12, toward the truss members 19. Such upward bowing or flexing of the member 26, in which position it will be supported by the members 19, causes the adjacent portions of the said supporting member 26 to move into yieldable engagement within the seats 23 and to consequently yieldably hold the working element 16 seated against the cross-piece 15. This is considered to be a feature of particular advantage in my invention in that possible injury to the working element 16 through warping of the stiles 10 or of the cross-piece 15 or other parts of the wash-board which may be formed of wood, is reduced to a minimum. Further, rattling of the working element 16 between the stiles 10 or between the supporting member 26 and the cross-piece 15, will be obviated. It is also to be noted that in use, while the weft wires 18 will be rigidly supported intermediate their ends by the truss members 19, still, such wires being resilient, will normally flex at their extremities, under the influence of a garment moved downwardly thereover, toward the supporting member 26, which movement of the said wires at their extremities will further tend to move the channel member 17 downwardly against the supporting member. It will be remembered that the supporting member 26 is also re-

silient and is thus disposed to yieldably resist such tendency of the channel members to move downwardly within the grooves 12. Consequently and as will be seen, the member 26 will, in use, yieldably support the 70 working element 16 adjacent its side edges.

The stiles 10 are preferably formed of wood and as will be readily understood may be easily constructed. The cap piece 11 is secured to the stiles in any suitable manner 75 and may thus be readily connected therewith. As previously explained, the head board 13 may then be readily arranged in position when the cross-piece 15 is then applied. The working element 16 and the 80 supporting member 26 are then disposed in position in the manner heretofore set forth.

It will thus be observed that I provide a wash-board which, while providing a rubbing surface or working element of novel 85 construction, is nevertheless, composed of few and simple parts which may be inexpensively manufactured. At the same time, it will also be seen that the construction provided will be thoroughly efficient and durable in use.

Having thus described my invention what I claim and desire to secure by Letters Patent is:—

1. A device of the character described including a supporting frame having side members channeled to receive a working element, a working element fitting in said channels, the said working element including truss members engaging the frame, and a resilient supporting member extending between said side members at one end of the working element and engaged by said truss members, the said supporting member being bowed to engage the working element. 95

2. A device of the character described including a supporting frame, a working element including channel members carried by the frame, said channel members being each provided with a concave seat, a resilient supporting member for the working element engaging in said seats, and a truss member connecting the said supporting member with the frame. 100

3. A device of the character described including a supporting frame, a working element carried thereby and including channel members, a resilient supporting member for the working element arranged at one end thereof at adjacent extremities of the channel members, and a truss member connected at one extremity to the frame and at its opposite extremity to said supporting member for maintaining the said supporting member flexed into engagement with the 115 said channel members whereby said supporting member provides a yieldable abutment for the working element. 120

4. A device of the character described including a supporting frame, a working ele- 130

ment carried thereby, a resilient supporting member for the working element, and a truss member connecting the supporting member with the frame whereby the supporting member is bowed intermediate its ends to engage the working element.

5. A device of the character described including a supporting frame, a working element carried thereby and including channel members, said channel members being each formed at one extremity with lugs bent to provide a concave seat, a resilient supporting member for the working element, and a truss member connecting the frame and supporting member whereby the supporting member is bowed to engage in said seats.

6. A device of the character described including a supporting frame, a working element including channel members having spaced side walls, a plurality of weft member having their extremities loosely received between the said side walls, a plurality of warp members constituting trusses secured at their upper extremities to the frame, the

said weft members being alternately crossed 25 first upon one side of one of said warp members and then upon the opposite side of the other warp member and providing upon each side of the working element a relatively smooth rubbing surface between said warp 30 members, a relatively rough rubbing surface adjacent the warp members, and a yieldable rubbing surface adjacent the said channel members, said weft members at their extremities being disposed for movement between the side walls of the said channel members, and a resilient supporting member for the working element engaging the said channel members and connected intermediate its ends to the lower extremities of the 40 said truss members.

In testimony whereof I affix my signature in presence of two witnesses.

HAROLD T. DAHLY.
